United States Patent Office

Des. 190,966
Patented July 25, 1961

190,966

FINGER RING

Harold N. Corbin, 1306 Denver St., Boulder City, Nev.

Filed Jan. 23, 1961, Ser. No. 63,648

Term of patent 14 years

(Cl. D45—10)

FIG. 1.

FIG. 2.

FIG. 3.

FIG. 1 is a plan view of a finger ring, showing my new design;

FIG. 2 is a front elevational view thereof; and

FIG. 3 is a side elevational view thereof.

I claim:

The ornamental design for a finger ring, as shown.
